UNITED STATES PATENT OFFICE.

FRANKLIN E. HAUN, OF SYRACUSE, NEW YORK.

TYPE-WRITING MACHINE.

No. 851,287.

Specification of Letters Patent.

Patented April 23, 1907.

Application filed December 24, 1906. Serial No. 349,219.

To all whom it may concern:

Be it known that I, FRANKLIN E. HAUN, a citizen of the United States, and a resident of Syracuse, in the county of Onondaga, in the 5 State of New York, have invented new and useful Improvements in Type-Writing Machines, of which the following, taken in connection with the accompanying drawings, is a full, clear, and exact description.

This invention pertains more particularly to so-called "front-strike" type-writing machines of that style in which the set of type-bars are pivoted in common to a segmental or inverted arc-shaped bar secured to the 15 frame of the machine in various ways.

The invention has special reference to the connection of the type-bar to the supporting-bar.

The objects of the invention are to provide 20 simple and effective means for readily and securely connecting the type-bars to the supporting-bar, and which shall facilitate the travel of the interposed antifriction bearings and shall also afford the advantages of permitting the type-bar to be removed from the 25 supporting-bar without disturbing the companion type-bars.

To that end the invention consists in the improved construction and combination of 30 the component parts of a coupling by means of which the type-bar is connected to the supporting-bar as hereinafter described and claimed.

My invention is fully illustrated in the accompanying drawings, in which

Figure 1 is a detail rear side view of the segmental bar shown partly in dotted lines and disposed in the position in which it is used in a "front-strike" writing-machine; a 40 type-bar being attached in accordance with my invention and represented as striking the usual platen also indicated by dotted lines; Fig. 2 is an enlarged transverse section of the segmental supporting-bar and a portion of a type-bar disposed in normal position; Fig. 3 is a vertical section taken on the line —X—X— in Fig. 2; Fig. 4 is a vertical section taken on the line —Y—Y— in Fig. 3; and Fig. 5 is an enlarged rear side view of a portion of the 45 segmental bar and a portion of a type-bar in printing position.

In the said drawings like numerals of reference indicate like parts:

—1—denotes the segmental bar formed round in cross-section and disposed in the 55 position of an inverted arc, and which may be attached in any suitable and convenient manner to the type-writer-frame (not shown) to serve as a common support for the set of type-bars, and —2—denotes the usual 60 platen designed to be mounted upon the carriage of the machine in the well known manner. The said segmental bar is provided with a series of circumferential V-shaped grooves —3— disposed radially in relation 65 to a common printing-point, indicated at —4—, on the platen, it being obvious that these grooves correspond in number to the type-bars to be employed.

—5—denotes the type-bar which may be 70 composed of any suitable metal and consists of the usual thin plate tapered to one end and carrying on said end the usual type indicated at —6—.

The larger end of the type-bar —5— is 75 formed with a segmental yoke —7— adapted to straddle the supporting-bar —1—. The ends of said yoke are formed with outwardly projecting ears —8— disposed with their opposed faces in lines extending tangentially 80 from diametric opposite sides of the supporting-bar —1—. Said ears are thus at sufficient distance apart to allow the yoke to be placed astride the supporting-bar or to be dismounted therefrom as may be required for 85 repairs or renewal. Within the said yoke

—7— is suitably secured a section of a bearing-ring —10— disposed concentric therewith and formed with an internal V-shaped groove —11— corresponding with a groove 90 —3— in the supporting bar. The two corresponding grooves —3— and —10— form a ball-race in which is disposed a set of anti-friction-balls —12— of sufficient number to extend more than one-half the distance 95 around the ball-race and grouped so as to leave at the end of the group a blank path for the travel of the group when the type-bar is swung to and from the platen as shown in Figs. 2 and 4.

While I prefer to provide the yoke with a section of bearing-ring —10— as shown, still at the same time it will be understood that the said ring-section may be dispensed with, in which instance the internal groove —11— 105 would obviously be formed in the yoke, and

the inner diameter of the yoke decreased proportionately with the thickness of the removed ring-section.

To confine the balls in the yoke I provide the ears —8— of said yoke with suitable stops extending into the ball-race or groove —3— of the supporting-bar —1—. I preferably form said stops by providing the ears —8— with eyes —9— and inserting in said eyes a rod —13— one end of which is provided with a head —13— bearing on the exterior of one ear and its opposite end is screw-threaded and engages threads in the eye of the other of said ears.

It will be observed that the rod —13— prevents the balls from escaping from the yoke as clearly shown in Figs. 2 and 4 of the drawings, and therefore said rod constitutes a barrier which terminates the passage of the balls at the opening between the ends of the yoke. Said barrier located as described and shown is essential to the invention inasmuch as it retains the balls arranged in a group extending around the greater portion of the circumference of the supporting-bar which serves to maintain the yoke in concentricity with said bar. This screw-rod extends through the groove —3— in the segmental bar but is out of contact with the bar to guard against friction and thus allow free action of the type-bar, said rod being at the ends of the ball-race, it serves as a guard which prevents the balls from escaping through the space between the ends of the yoke. The group of balls extending around the greater portion of the circumference of the supporting-bar forms a hook-shaped coupling between the yoke and the supporting-bar. Said coupling can only be broken by removal of the rod —13— and thus allowing the balls to escape from the ball-race.

The ends of the yoke are beveled correspondingly with the V-shaped groove —3—, as indicated at —14—, and are spaced sufficient distance apart to allow them to clear the segmental bar, and thus the type-bars may be readily and independently removed from the segmental bar and placed thereon by simply taking off the screw-rod —13—.

The ear having the threaded eye is preferably split lengthwise as indicated at —15—, to permit the ear to be expanded slightly by the rod entering the eye —9— of said ear the threads of the rod are thus caused to obtain a firm hold in the ear and effectually prevent the rod from working loose. It will be observed that by tightening the rod from time to time, the yoke and bearing ring-section may be contracted slightly to take up the wear on the bearings.

What I claim is:

1. The combination, with the supporting-bar, of the type-bar provided with a yoke

straddling said supporting-bar and formed with an opening at its ends, balls in the yoke arranged in a group occupying more than one half of the circumference of the supporting-bar, and means for arresting the balls at the ends of the aforesaid opening.

2. The combination, with the supporting-bar, of the type-bar provided with a yoke surrounding the greater portion of the circumference of the supporting-bar, and formed with ears on its ends, balls in the yoke arranged in a group occupying more than one half of the circumference of the supporting-bar, and means removably attached to the aforesaid ears and terminating the ball-bearings at the ends of the yoke.

3. In combination with the supporting-bar provided with circumferential ball-bearings, the type-bar formed with a segmental yoke straddling the supporting-bar and terminating in outwardly projecting ears disposed with their opposed faces in lines extending tangentially from opposite sides of the supporting-bar, balls arranged in a group occupying more than one half of the circumference of the supporting-bar and leaving a blank path from the end of the group to the adjacent ear, and means attached to the aforesaid ears and terminating the passage of the balls thereat.

4. In combination with the supporting-bar provided with circumferential grooves, the type-bar formed with a segmental yoke straddling the supporting-bar and terminating in ears disposed with their opposite sides in lines extending tangentially from opposite sides of the supporting-bar, a transverse rod extending through the groove of the supporting-bar and secured to the aforesaid ears, and balls interposed between the yoke and supporting-bar and grouped to leave a blank path between one end of the group and transverse rod.

5. In combination with the supporting-bar provided with circumferential grooves, the type-bar formed with a segmental yoke straddling the supporting-bar and terminating in outwardly projecting ears disposed with their opposed sides in lines extending tangentially from opposite sides of the supporting-bar, said ears being provided with eyes disposed in line with each other and one of said eyes screw-threaded and the said ear split lengthwise of the eye, and a bolt inserted in said eyes and having one end provided with a head and the opposite end screw-threaded and passing through the eye of the split ear and clamped therein by compression of the said ear, and balls interposed between the yoke and supporting-bar and grouped to leave a blank path between one end of the group and the aforesaid rod as set forth.

6. In combination with the supporting-bar, a type-bar equipped with a coupling con-

sisting of a yoke of segmental shape surrounding the greater portion of the circumference of said supporting-bar and having between its ends an opening of a width approximately 5 equal to the diameter of the supporting-bar, balls interposed between the yoke and supporting-bar and grouped to leave a blank path between the front of the group and the

aforesaid opening, and a rod extending across the opening and adjustably connected to the ends of the yoke to contract the same and compensate for the wear of the ball-bearings.

FRANKLIN E. HAUN.
